COMPOUND ENGINE SYSTEM

Paul M. Morse, R.F.D. 1, Carlinville, Ill., assignor of fifty percent to Thomas M. Morse, Carlinville, Ill.

Filed Oct. 10, 1958, Ser. No. 766,527

7 Claims. (Cl. 123—51)

This invention comprises a novel compound engine system and more particularly relates to an internal combustion engine wherein a multiple piston system operating in a single cylinder imparts reverse rotations to two interconnected parallel crankshafts.

The primary purpose of this invention is to provide an internal combustion engine wherein a multiple piston system imparts simultaneous rotation and power to a pair of contra-rotating crankshafts and for effecting a dynamic balance of the thrust, inertia effects and vibration of the reciprocating pistons and of the crankshafts.

A further object of the invention is to provide an internal combustion engine in accordance with the preceding object wherein a more effective development of the power derived from a reciprocating piston engine may be obtained and whereby the number of power impulses obtained from the piston assembly within a single cylinder during a single rotation of the crankshaft may be increased.

A further important object of the invention is to provide an internal combustion engine wherein there is obtained a reduction in the weight of the engine per horsepower, a greater durability and reliability of the engine is secured and wherein a simplified construction, lower initial cost and upkeep is realized.

Still another object of the invention is to provide an engine in accordance with the preceding objects which shall utilize a less expensive and a safer fuel.

Yet another important object of the invention is to provide an engine or combustion engine which will eliminate the usual electrical ignition system and the detrimental side effects of the latter such as interference with radio and television transmission and reception.

Still another object of the invention is to provide an internal combustion engine in accordance with the preceding objects which will provide a more effective and compact exhaust and muffler system and one which will be highly efficient in operation.

A more specific object of the invention is to provide an internal combustion engine having a plurality of pistons in a single cylinder and wherein the piston inertia at the reversal of motion of the same is utilized to cushion the reversal of the pistons and to convert kinetic energy of the same for compression of the working fluid in the combustion chambers of the engine.

Yet another object of the invention is to provide an internal combustion engine as set forth hereinbefore which shall be especially adapted for operating a pair of oppositely rotating propellers thus being especially useful for aircraft by eliminating or minimizing gyroscopic effects, torque reactions and the like.

A still further object of the invention is to provide in an engine of the character above set forth an effective pressure lubrication of the interior of the pistons and their rubbing surfaces.

These together with other objects and advantages which will become subsequently apparent reside in the details of construction and operation as more fully hereinafter described and claimed, reference being had to the accom-

2

panying drawings forming a part hereof, wherein like numerals refer to like parts throughout, and in which:

Figure 1 is a front elevational view showing a portion of an aircraft provided with a pair of contra-rotating propellers for which the propulsive power plant of this invention is particularly adapted;

Figure 2 is a view in horizontal longitudinal section through the central portion of the engine in accordance with this invention, and showing the transmission and 10 piston arrangement for the same, with the exhaust manifold and muffler being shown in elevation and a part hereof being broken away;

Figure 3 is a vertical longitudinal sectional view through the working cylinder of the engine of Figure 2, 15 being taken substantially upon the plane indicated by the section line 3—3 of Figure 2, certain concealed parts being shown in dotted lines therein and certain parts being broken away and omitted therefrom;

Figure 4 is a vertical transverse sectional view taken 20 substantially upon the plane indicated by the section line 4—4 of Figure 2 and showing in particular one of the lubricating pumps and its driving means and also the means for actuating the fuel injectors of the engine;

Figure 5 is a vertical transverse sectional view taken 25 substantially upon the plane indicated by the section line 5—5 of Figure 2 and showing in particular the exhaust discharge system of one of the combustion chambers of the engine;

Figure 6 is a vertical transverse sectional view taken 30 substantially upon the plane indicated by the section line 6—6 of Figure 2 and showing in particular the compressed air charging system of the engine;

Figure 7 is a view similar to Figure 3 but showing the 35 pistons therein in elevation and showing the positions of the pistons and crankshafts at the innermost stroke of the latter; and

Figure 8 is a view similar to Figure 7 but showing the 40 position of the pistons at the outermost stroke of the crankshafts.

Figure 1 shows by way of example a particular environment or use for which the propulsive plant of this invention is especially designed. As shown in this figure any suitable form of aircraft designated by the numeral 10 is provided with a pair of propellers 12 and 45 14 which rotate in opposite directions indicated by the arrows in this figure. The power plant of this invention includes a pair of oppositely rotating crankshafts, each of which is directly connected to one of the propellers 12 and 14 for thereby operating the latter in opposite directions.

As shown more particularly in Figures 2 and 3, the power plant of this invention may comprise a single cylinder receiving therein multiple pistons for delivering power to a pair of crankshafts. It will be understood, 55 however, that the principles of the invention comprehend a construction having a plurality of cylinders which may be disposed in parallel arrangement between and operatively connected to the pair of parallel crankshafts.

In the embodiment illustrated there is provided a single 60 elongated cylinder 20 which at its two open opposite ends is provided with mounting flanges 22, each of which is secured as by a fastening bolt 24 to the corresponding mounting flange 26 of the crankcases 28 and 30. Each of these crank cases is provided with suitable bearings 32 65 therein by means of which is journaled one end portion of a crankshaft 34 for the casing 28 and 36 for the crankcase 30. These crankshafts have connected thereto conventional connecting rods 38 and 40 which extend into the opposite ends of the cylinder 20.

The crankcases 28 and 30 as shown in Figure 2 project outwardly beyond the ends of the cylinder and include housings 42 and 44 through which extend the 70

crankshaft 34 and 36, and in which the crankshafts are further journaled as at 46 and 48. In these two housings the crankshafts are provided with gears each designated by the numeral 50 and which are engaged by gears 52 provided on the opposite extremities of a shaft 54 which comprises a means connecting the two crankshafts for reverse rotation.

As will be observed from Figures 2, 3, 7 and 8, the cylinder 20 is provided with a plurality of air cooling fins as at 56, while the crankcases and their housings 42 and 44 are provided with a plurality of similar fins as at 58. It will be understood, however, that other suitable cooling means other than air cooling can be provided for this engine in accordance with conventional practice.

With continuing reference to Figures 2 and 3 it will be observed that the two connecting rods 38 and 40 are pivotally secured as by pins 60 and 62 to the opposite ends of a pair of concentric telescoping tubes 64 and 66 respectively. It will be observed that the inner tube 64 is open at both of its ends and along its length is provided with a series of radial ports 68 for a purpose to be subsequently apparent. The outer tube 66 is likewise open at both of its ends so that the pair of concentric tubes freely communicate with the two crankcases through the open ends of the attached cylinder. The outer tube and its mid-portion is provided with a pair of longitudinally extending diametrically disposed slots 70 and the inner tube at its inward end carries a transversely extending cross pin 72 which extends through the slot 70 to the exterior thereof for a purpose to be subsequently apparent. As so far described it will thus be apparent that with the two crankshafts having their throws disposed 180° apart, that the connecting rods and the tubes attached thereto will be caused to reciprocate towards and from each other with a telescoping motion.

A multiple piston system is slidably received within the cylinder 20 and is disposed in the annular space between the pair of concentric tubes and the wall of the cylinder. The piston assembly includes a pair of pistons 80 and 82 which are screw-threadedly engaged upon the opposite ends of the outer tube 66 and are thus held in fixed relation with respect to each other and are reciprocated with the outer tube by the connecting rod 40 upon operation of the crankshaft 36. As will be readily understood in accordance with conventional practice, suitable piston rings 84 are provided for these two pistons upon their periphery to establish a fluid-tight seal with the wall of the cylinder 20 in which the pistons reciprocate.

There is also provided an intermediate piston 86 which is fixedly secured at its mid-portion to the previously mentioned pin 72 and thus reciprocates in the annular compartment lying between the concentric tubes and the surrounding cylinder, in response to reciprocation of the inner tube 64 by the connecting rod 38 and the crankshaft 34.

The intermediate piston is double-headed and provided with a piston head 88 and 90 at the opposite ends thereof and which heads are opposed to the cylinders 80 and 82 previously mentioned. Suitable external and internal piston rings 92 and 94 respectively are carried by each of the piston heads 88 and 90 for establishing sealing engagement with the cylinder wall and the outer tube 66 respectively.

It will further be observed that the intermediate piston together with the two outer pistons defines with the cylinder and with the outer tube a pair of annular combustion chambers, that at 96 being disposed between the piston 80 and the piston head 88 of the intermediate piston, while that at 98 is disposed between the outer piston 82 and the adjacent piston head 90 of the intermediate cylinder.

As so far described it will now be understood that upon rotation of the crankshafts in opposite directions, the

pair of fixedly spaced pistons and the intermediate piston will be reciprocated in opposite directions, thereby alternately expanding and contracting the chambers 96 and 98 in sequence. The expansion and contraction of these chambers constitutes the working strokes of the piston assembly.

From Figure 2 it will be further noted that intermediate the ends of the intermediate piston there is provided upon its exterior surface a circumferentially extending recess 100, and a further longitudinally elongated inner recess 102 is formed upon the inner surface thereof. The outer recess 100 provides a chamber between the intermediate piston and the wall of the cylinder, while the inner recess 102 provides a similar chamber between the interior of the intermediate piston and the exterior surface of the outer tube 66. A plurality of bores or ports 104 extend through the intermediate piston to establish communication between these two recesses.

Means are provided for lubricating the inner relatively moving surfaces of the telescoping concentric tubes, and of the intermediate piston as well as the other working parts of the engine. For this purpose, as will be best apparent from Figure 2 in conjunction with Figure 4, it will be understood that each of the crankcase housings 42 and 44 has mounted in the bottom or sump thereof a lubricating gear pump assembly which is designated generally by the numeral 110 and is of a conventional design, the same including an inlet passage 112 communicating with the interior of the crankcase for receiving lubricant from the sump portion thereof, together with a lubricant discharge passage 114 by which lubricant is discharged from the gear pump. The gear pumps are driven from the crankshafts 34 and 36 through the agency of gears 116 on each crankshaft which gears mesh with the pump driving gear 118 as shown in Figure 4.

The lubricant discharge conduits 114 each communicate with the cylinder 20 at its mid-portion and discharge into the previously mentioned exterior annular recess 100 of the intermediate piston. From thence the lubricant under pressure passes through the ports 104 to the inner recess 102, from whence it travels through the slot 70 either directly to the interior of the outer tube 66 or by further means of the bores or ports 68 to the inner tube of the interior of the latter. Thus, the lubricant is enabled to satisfactorily lubricate the exterior surface of the intermediate piston; the exterior surface of the outer tube 66 between the latter and the intermediate piston; the adjacent surface of the concentric telescoping tubes; the pins 60, 72 and 62; and will then flow from the open ends of the cylinder into the two crankcases to thus lubricate the crankshafts and the working parts therein.

Further means are provided for supplying combustion components to the interior of the combustion chambers 96 and 98 of the engine, for igniting these components and for educting combustion products therefrom.

Although the construction of the engine and its mechanism for producing expansible working chambers is applicable to other apparatuses and internal combustion engines, and to other types of engines and cycles of operations, it is especially applicable as regards the economy of fuel and the obtaining of a low ratio of weight to horsepower developed, for use with the well-known two cycle diesel operation.

For that purpose there are provided a pair of air compressors 120 each of which is secured as by fastening bolts 122 to a mounting flange 124 projecting laterally from the cylinder at the inner end of the working chambers 96 and 98. These compressors may be of any desired character but are preferably of the conventional centrifugal compressor type, being shown more clearly in Figure 6. Inasmuch as the details of the blower or compressors 120 form no part of the invention claimed herein, and since the invention as claimed is not limited to any particular construction of the air compressors, a further description of the same is deemed to be unnecessary for the purposes of this invention. However, there

is provided an annular manifold 126 surrounding the cylinder 20 at each of the combustion chambers 96 and 98 and a plurality of air inlet ports 128 establish communication from the interior of this manifold to the interior of the cylinder and the combustion chambers therein.

The compressors are supported as above described upon the wall of the cylinder, but their rotors 130 are fixedly secured to the connecting shaft 54 previously mentioned. Thus, the means which interconnects the two crankshafts for contra-rotation is employed to drive the pair of compressors, each of which supplies compressed air to one of the working chambers of the engine.

At the outer end of each of the combustion chambers 96 and 98, the crankcase is encircled by an exhaust manifold 140 which communicates with the interior of the working chamber as by a series of circumferentially spaced exhaust ports 142, this arrangement being shown best in Figure 5. The exhaust manifolds are connected by exhaust pipes 144 to a common exhaust muffler 146 having one or more exhaust discharge pipes 148. This muffler may be of any conventional design but of course must possess sufficient capacity to handle the combined exhaust products of the two combustion chambers 96 and 98. Inasmuch as the details of the muffler form no part of the invention claimed herein, it has not been deemed necessary to further illustrate or describe the same.

In order to supply fuel to the combustion chambers and effect ignition of the same therein there is provided any conventional type of fuel injection pump designated generally by the numeral 160. One such pump is provided for each of the combustion chambers, the pumps being mounted upon the compartments 42 and 44 and having fuel delivery lines 162 which extend from the pumps into the combustion chambers 96 and 98 at substantially the midportion of the same. If desired, any conventional type of fuel injection nozzles can be provided at the exit of these fuel delivery conduits for appropriately discharging and spraying the liquid fuel into the interior of the combustion chambers.

Conveniently, the pumps each include a plunger or piston 164 which is operated by a cam 166 formed upon the crankshafts 34 and 36 in the compartments 42 and 44 respectively. It will of course be understood that the operation of the injection pumps is appropriately timed with respect to the position of the reciprocating pistons to inject the fuel into the compressed air in the combustion chamber in properly timed relation to effect ignition by compression existing in the chamber and thus producing the power stroke of the pistons.

It will further be observed that the compressed air inlet ports are so positioned as to be controlled by the intermediate piston, and thus will be opened at the time the associated working chamber would have reached its maximum volume, at which time the other piston 80 or 82 will also have opened the exhaust ports thus permitting the combustion products to discharge from the working chambers. The incoming compressed air will thus facilitate scavenging of the exhaust products upon the completion of the working stroke, and will charge the chamber with compressed air in readiness for the following compression stroke. When the compression stroke has been substantially completed and the working chamber reduced to its minimum volume, the cam 166 will deliver the timed injection of fuel into the compressed air, thus producing ignition and combustion and initiating the next working stroke of the engine.

In the position shown in Figures 2 and 3, the various pistons are at their intermediate positions during their operation. In the position shown in Figure 7, it will be observed that the combustion chamber 96 has completed its working stroke, since the air inlet ports are open and compressed air is being discharged thereinto scavenging the cylinder and driving exhaust products out of the open

exhaust ports. At the same time, the combustion chamber 98 has completed its compression stroke and the associated fuel injector pump has injected a fuel charge thereinto and initiated combustion therein. Upon 180° rotation of the two crankshafts, the pistons will then assume the position shown in Figure 8 at which time it will be observed that the left hand chamber 96 will have completed its compression stroke, while the right hand chamber 98 will have completed its power stroke.

It will be further noted that with this engine the relative displacement of the pistons in their working chambers is twice the throw of their crankshafts since both the pistons move simultaneously towards and from each other in a given working chamber. Further, since each

15 piston in a working chamber is connected to both crankshafts, the force of the explosion will be equally imparted to both crankshafts simultaneously thus producing a balancing of the forces involved as well as of the reciprocating and reversing inertias and masses of the pistons.

20 It will be further noted that as a pair of pistons completes its compression stroke, their inertia is cushioned as the pistons reverse their reciprocation by virtue of the compressed gases therebetween, and the kinetic energy thus absorbed by the compressed gases is returned to the pistons as they recede from each other. Thus the transmission of strains to the transmission mechanism of the engine is reduced to a minimum as well as the inertias and shocks arising from the usual reversal of piston reciprocation.

25 30 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An internal combustion engine comprising a cylinder, a crankcase secured to each end of said cylinder, a pair of parallel crankshafts each journaled in one of said crankcases, means connecting said crankshafts for reverse rotation, a pair of spaced pistons rigidly connected together and slidably in said cylinder and connected to one of said crankshafts, an intermediate piston 40 connected to the other crankshaft and slidably disposed in said cylinder between said pair of pistons, the spaces in said cylinder between the opposite ends of said intermediate piston and said pair of pistons defining a pair of combustion chambers, means for delivering combustion components to said chambers in succession, for igniting said components and for exhausting combustion products therefrom, a pair of telescoping tubes each connected to one of said crankshafts, means connecting one tube to said intermediate piston, means connecting the other tube to said pair of pistons, said telescoping tubes providing an opening extending longitudinally therethrough and communicating with said crankcases, whereby the volume displaced by one of said spaced pistons 45 upon movement of the latter towards the adjacent crankcase is substantially equalled by the simultaneous movement of the other spaced piston away from its adjacent crankcase thereby maintaining substantially equal and constant air pressure in each of said crankcases.

60 65 70 75 2. An internal combustion engine comprising a cylinder, a crankcase secured to each end of said cylinder, a pair of parallel crankshafts each journaled in one of said crankcases, means connecting said crankshafts for reverse rotation, a pair of spaced pistons rigidly connected together and slidably in said cylinder and connected to one of said crankshafts, an intermediate piston connected to the other crankshaft and slidably disposed in said cylinder between said pair of pistons, the spaces in said cylinder between the opposite ends of said intermediate piston and said pair of pistons defining a pair

of combustion chambers, means for delivering combustion components to said chambers in succession, for igniting said components and for exhausting combustion products therefrom, a pair of telescoping tubes each connected to one of said crankshafts, means connecting one tube to said intermediate piston, means connecting the other tube to said pair of pistons, said telescoping tubes providing an opening extending longitudinally therethrough and communicating with said crankcases, means for circulating lubricant through said telescoping tubes and said crankcases.

3. An internal combustion engine comprising a cylinder, a crankcase secured to each end of said cylinder, a pair of parallel crankshafts each journaled in one of said crankcases, means connecting said crankshafts for reverse rotation, a pair of spaced pistons rigidly connected together and slidable in said cylinder and connected to one of said crankshafts, and intermediate piston connected to the other crankshaft and slidably disposed in said cylinder between said pair of pistons, the spaces in said cylinder between the opposite ends of said intermediate piston and said pair of pistons defining a pair of combustion chambers, means for delivering combustion components to said chambers in succession, for igniting said components and for exhausting combustion products therefrom, a pair of telescoping tubes, means connecting each tube to one of said crankshafts, each of said pistons having an axial opening therethrough, the outer of said tubes being disposed in all of the openings of said pistons and rigidly connected to said pair of pistons, said outer tube having a longitudinally extending diametrical slot in a mid-portion thereof, a pin slidably disposed through said slot and secured to both the inner of said tubes and to said intermediate piston, said telescoping tubes providing an opening extending longitudinally therethrough and communicating with said crankcases, whereby the volume displaced by one of said spaced pistons upon movement of the latter toward the adjacent crankcases is substantially equalled by the simultaneous movement of the other spaced piston away from its adjacent crankcase thereby maintaining substantially equal and constant air pressure in each of said crankcases.

4. An internal combustion engine comprising a cylinder, a crank secured to each end of said cylinder, a pair of parallel crankshafts each journaled in one of said crank cases, means connecting said crankshafts for reverse rotation, a pair of spaced pistons rigidly connected together and slidable in said cylinder and connected to one of said crankshafts, an intermediate piston connected to the other crankshaft and slidably disposed in said cylinder between said pair of pistons, the spaces in said cylinder between the opposite ends of said intermediate piston and said pair of pistons defining a pair of combustion chambers, means for delivering combustion components to said chambers in succession, for igniting said components and for exhausting combustion products therefrom, a pair of telescoping tubes, means connecting each tube to one of said crankshafts, each of said pistons having an axial opening therethrough, the outer of said tubes being disposed in all of the openings of said pistons and rigidly connected to said pair of pistons, said outer tube having a longitudinally extending diametrical slot in a mid-portion thereof, a pin slidably disposed through said slot and secured to both the inner of said tubes and to said intermediate piston, an annular recess upon the exterior surface of said intermediate piston, ports establishing communication between said recess and the axial opening of said intermediate piston, ports in said inner tube communicating the interior of the latter with said slot and with said intermediate piston ports, the interior of said tubes communicating with said crankcases, means for circulating lubricant from said crankcases to said recesses and from thence through said tubes to said crankcases.

5. An internal combustion engine comprising a cyl-

10

inder, a crankcase secured to each end of said cylinder, a pair of parallel crankshafts each journaled in one of said crankcases, means connecting said crankshafts for reverse rotation, a pair of spaced pistons rigidly connected together and slidable in said cylinder and connected to one of said crankshafts, an intermediate piston connected to the other crankshaft and slidably disposed in said cylinder between said pair of pistons, the spaces in said cylinder between the opposite ends of said intermediate piston and said pair of pistons defining a pair of combustion chambers, means for delivering combustion components and for exhausting combustion products therefrom, said last mentioned means comprising air blowers driven from said connecting means and delivering compressed air from each blower to one of said combustion chambers fuel injection means operated each by one of said crankshafts and injecting fuel into a combustion chamber and effecting ignition therein and exhaust means educting products of combustion from each combustion chamber, a pair of telescoping tubes each connected to one of said crankshafts, means connecting one tube to said intermediate piston, means connecting the other tube to said pair of pistons, said telescoping tubes providing an opening extending longitudinally therethrough and communicating with said crankcases, whereby the volume displaced by one of said spaced pistons upon movement of the latter towards the adjacent crankcase is substantially equalled by the simultaneous movement of the other spaced piston away from its adjacent crankcase thereby maintaining substantially equal and constant air pressure in each of said crankcases.

6. An internal combustion engine comprising a cylinder, a crankcase secured to each end of said cylinder, a pair of parallel crankshafts each journaled in one of said crankcases, means connecting said crankshafts for reverse rotation, a pair of spaced pistons rigidly connected together and slidable in said cylinder and connected to one of said crankshafts, and intermediate piston connected to the other crankshaft and slidably disposed in said cylinder between said pair of pistons, a pair of telescoping tubes each connected to one of said crankshafts, means connecting one tube to said intermediate piston, means connecting the other tube to said pair of pistons, said telescoping tubes providing an opening extending longitudinally therethrough and communicating with said crankcases, whereby the volume displaced by one of said spaced pistons upon movement of the latter towards the adjacent crankcase is substantially equalled by the simultaneous movement of the other spaced piston away from its adjacent crankcase thereby maintaining substantially equal and constant air pressure in each of said crankcases.

7. The combination of claim 6 including means for delivering combustion components to the combustion chambers of said engine, said last mentioned means comprising air blowers driven from said connecting means and delivering compressed air from each blower to the combustion chambers, fuel injection means operated each by one of said crankshafts and injecting fuel into a combustion chamber and effecting ignition therein and exhaust means educting products of combustion from each combustion chamber.
